HAIR DRYING APPARATUS

Filed July 8, 1930

UNITED STATES PATENT OFFICE

CARL FUCHS, OF ZURICH, SWITZERLAND

HAIR-DRYING APPARATUS

Application filed July 8, 1930, Serial No. 466,504, and in Switzerland May 29, 1929.

Applications have been filed in England May 28, 1930, No. 16,460, and in Switzerland, May 29, 1929, No. 65,466.

The hair-drying apparatus according to the present invention secures an easier and more uniform drying of the hair, the uniform drying being independent of the action of the person using the apparatus. In the first place, the invention consists in that a protective hood, which is permeable to air, is unrotatably mounted in a bell-shaped drying air distributor which is rotated mechanically. Furthermore, the bell-shaped air distributor is preferably provided with a plurality of radial hollow arms. Further, the air aspirator and the drive for rotating the air distributor are preferably mounted in a hollow base of the apparatus, the air being passed through a column and the rotation of the air distributor being effected by a flexible shaft and toothed wheel gear.

The invention is explained with reference to the accompanying drawing, in which

Figure 1 is a side view of one construction, Figure 2 shows a portion of the construction in section,

Figure 3 is a section along the line A—B in Figure 2,

Figure 4 shows the upper part of a second construction, and

Figure 5 shows the lower portion of the second construction.

In Figures 1 to 3, 1 is a hollow base with a stand 2. 3 are air inlet openings. In the base 1 are a rotating and heating motor 5 and an air aspirator 4 in the form of a fan. 6 is a hollow column, on the top of which is located a flexible tube 7, terminating in a pipe 8. An air-permeable protective hood 9 is attached securely to the said pipe 8. The bell-shaped drying air distributor is mounted rotatably about the pipe by means of ball bearings. The said air distributor has hollow arms 12, which are provided with nozzles 13, directed towards the central axis, for the air. The air can enter the hollow spaces of the arms 12 through radial holes in the pipe 8. A spur wheel 14 is secured to the air distributor 11, the said spur wheel being rotated by a bevel gear on the shaft of the motor 5,

a flexible shaft 16 and a second spur wheel 18. 17 is a bearing for the flexible shaft 16. An arm 19 located on the pipe 8 pivotally engages a clip 20 which may be clamped securely at different heights on the column 6.

When the motor 5 is connected to the mains, the fan 4 draws in outside air, which is warmed by the motor 5 and is forced through the conduit 6, 7, 8 into the air distributor and out of the nozzles 13. At the same time, the air distributor is slowly and evenly rotated mechanically by the motor 5, while the protective hood 9 remains stationary. The flexible shaft enables the angle which the central axis of the air distributor and of the protective hood makes with the axis of the column to be varied, without interrupting the drive.

In the construction shown in Figures 4 and 5, an air supply pipe 21, passing through the base 1, is connected to the hollow column 6, and may be connected to a central source of hot air. Moreover, a small rotating motor 22 is mounted on the bearing 17 for rotating the toothed wheel 18.

I claim:

1. In an apparatus for hair-drying, the combination of a bell-shaped drying air distributor, air outlet openings on the inner side of same, a conduit for supplying air to the air distributor, an air-permeable protective hood within the air distributor and means for mechanically rotating the air distributor about the stationary protective hood.

2. In an apparatus for hair-drying the combination of a bell-shaped drying air distributor, having a plurality of radial arms, air outlet openings on the inner side of the arms, a pipe for supplying air to the air distributor, an air-permeable protective hood within the air distributor, and means for mechanically rotating the air distributor about the stationary protective hood.

3. In an apparatus for hair-drying, the combination of a bell-shaped drying air distributor, air outlet openings on the inner side of same, a conduit for supplying air to the air distributor, an air-permeable protective hood within the air distributor, and means for mechanically rotating the air distributor

about the stationary protective hood, distributor and protective hood being angularly adjustable on a column, the column being a part of the air supply conduit.

- 5 4. In an apparatus for hair-drying, the combination of a bell-shaped drying air distributor, air outlet openings on the inner side of same, a conduit for supplying air to the air distributor, an air-permeable protective hood within the air distributor, means for mechanically rotating the air distributor about the stationary protective hood, distributor and protective hood being angularly adjustable on a column, the column being a part
- 10 15 of the air supply conduit, a hollow base on the column containing a rotating and heating motor and an air aspirator, the rotating mechanism being connected to the air distributor through a flexible shaft and toothed
- 15 20 26 wheel gear, the air aspirator communicating with the column.

In testimony whereof I have signed my name to this specification.

CARL FUCHS.
